United States Patent Office

Des. 200,969
Patented Apr. 27, 1965

200,969

CANISTER

Leo F. Wildgen, Minneapolis, Minn., assignor to Flambeau Plastics Corporation, a corporation of Wisconsin

Filed Oct. 8, 1964, Ser. No. 82,105

Term of patent 7 years

(Cl. D44—6)

FIG. 4.

FIG. 5.

FIGURE 1 is a top view of a canister embodying my new design;

FIGURE 2 is a side elevational view of the same;

FIGURE 3 is a bottom view of the same;

FIGURE 4 is a front elevational view;

FIGURE 5 is a rear view of the same.

I claim:

The ornamental design for a canister, substantially as shown.
